UNITED STATES PATENT OFFICE.

CHARLES J. ANDERSON, OF PHILADELPHIA, PENNSYLVANIA, ASSIGNOR TO WILLIAM J. LAWSON, OF PHILADELPHIA, PENNSYLVANIA.

MAILING-BOX.

1,191,057.

Specification of Letters Patent. Patented July 11, 1916.

Application filed August 21, 1915. Serial No. 46,693.

To all whom it may concern:

Be it known that I, CHARLES J. ANDERSON, a citizen of the United States, residing in Philadelphia, Pennsylvania, have invented 5 certain Improvements in Mailing-Boxes, of which the following is a specification.

My invention relates to certain improvements in mailing boxes, particularly those adapted for mailing articles by parcels post.

10 One object of the invention is to provide a receptacle, or container, within the box, for the string or cord.

A further object of the invention is to provide suitable means by which the string, or 15 cord, is anchored to the box.

In the accompanying drawings: Figure 1 is a perspective view, showing the box made in accordance with my invention and having the cord wrapped thereon and tied thereto;

20 Fig. 2 is a longitudinal sectional view on the line *a—a*, Fig. 3; Fig. 3 is a sectional plan view on the line *b—b*, Fig. 2; Fig. 4 is a sectional perspective view; and Fig. 5 is a detached perspective view, showing the spool 25 and the cord attached thereto.

Referring to the drawings, 1 is the body portion of the box made in the usual manner and 2 is the lid. At the center of the lid, in the present instance, is a projection in the 30 form of a button 3 around which the cord is passed when it is wrapped. At one end of the box, in the present instance, is a receptacle 4, formed by a casing 5 in which is a cord 6. This cord is wrapped around a 35 spool 7 and is tied thereto, as in Fig. 5. The end of the cord extends through an opening 8 at the side of the box. After the goods have been packed ready for delivery or shipment, the cord is drawn out of the box, freely 40 unwinding from the spool, and is then wrapped around the box in any suitable manner and around the button as an anchor, preferably as shown in Fig. 1, and is tied at the button or at the opening 8 in the box in 45 such a manner that, in case of inspection, the cord can be unfastened and unwound so

that the lid can be removed and the contents examined, after which the cord can be replaced.

The length of the cord is proportionate to 50 the size of the box, consequently there is no undue waste and a great saving will result by the use of a box of this character, particularly in establishments where a large number of mail orders are sent out daily. 55

The cord is always available and is of proper length to secure the box for mailing purposes. In some instances, instead of the spool, other means of fastening and for retaining the fixed end of the cord may be used 60 without departing from the essential features of the invention, but I prefer to use the spool as it is more readily applied and gives a firm anchorage for the cord when the end is drawn from the box. 65

While I have shown the receptacle at one end of the bottom of the box, it may be at the center of the box, or may be carried by the lid without departing from the spirit of the invention. The button, or its equivalent, 70 may be located at any point on the lid or the body of the box.

In some types of boxes, it may be preferable to locate the spool or cord in the lid of the box so as to leave the body of the box 75 entirely free for packing purposes.

I claim:

1. The combination of a box having a body portion and a lid; a receptacle at one end of the body portion, the body portion 80 having an opening communicating with the receptacle; and a retaining cord located within the receptacle and having one end anchored to the box so that one end of the cord can be withdrawn from the box through 85 the opening and wrapped around the box and secured.

2. The combination of a box having a body portion and a lid, the body portion having a receptacle at one end; a spool with- 90 in the receptacle; a cord wrapped around the spool and attached thereto; and an opening

in the box through which one end of the cord extends so that the cord can be drawn and wrapped around the box.

3. The combination in a box, of a body portion and a lid; a receptacle at one end of the body portion; a hole in the body portion communicating with the receptacle; a spool within the receptacle; a cord wrapped

around the spool and attached thereto, the free end of the cord extending through the opening; and a button on the lid for anchoring the cord after it has been drawn from the receptacle and wrapped around the box.

CHARLES J. ANDERSON.

Copies of this patent may be obtained for five cents each, by addressing the "Commissioner of Patents, Washington, D. C."
